UNITED STATES PATENT OFFICE.

GEORGE S. COLEMAN, OF NEWARK, NEW JERSEY.

ELECTRIC SIGN.

1,250,143.

Specification of Letters Patent. Patented Dec. 18, 1917.

Application filed October 21, 1916. Serial No. 126,862.

To all whom it may concern:

Be it known that I, GEORGE S. COLEMAN, a citizen of the United States, residing at Newark, in the county of Essex and State 5 of New Jersey, have invented certain new and useful Improvements in Electric Signs, of which the following is a specification.

The present invention relates to automatic signs of that general type known as electrically-operated signs and it has for its objects, among others, to provide a novel sign having a motion or moving picture effect, for advertising purposes, adaptable to windows, building and store fronts, roofs, along 10 the line of a railroad or any other desired position, and made in any size to suit the conditions or circumstances under which it may be desired to operate the same.

Another object of the invention is to provide an automatic electrically-operated sign whereon the various figures representing the persons or other objects may be shown in action while going through various movements, as in a store, or a restaurant, or in the 20 street for instance, the persons being represented as if they were moving or in motion, and the length of time that each person or object shall be displayed being automatically controlled by suitable means, as for instance 25 a flasher.

Another object of my invention is to provide an improved construction of flasher for operating the various incandescent lamps, which flasher shall be of extremely simple 30 and compact construction whereby to occupy but little space and so combined with the other features of my apparatus as to render the whole portable and convenient to move from place to place.

40 My improved flasher is of such construction that the same will not be liable to get out of order and is very inexpensive to manufacture.

Various other objects and advantages of 45 the present invention will be apparent from the following description when taken in connection with the accompanying drawings.

The invention consists in the novel construction, arrangement and combinations of 50 parts as hereinafter fully described and then specifically pointed out in the appended claims.

In the drawings:

Figure 1 represents a front view of one 55 form of sign embodying my present invention.

Fig. 2 is a vertical cross section of the same on line 2-2 of Fig. 1, the electric motor being shown in elevation.

Fig. 3 is a side view of the brush-carrying 60 arm and brushes.

Fig. 4 is a transverse section of said arm and one of the brushes.

Fig. 5 is a detail section on an enlarged scale showing the relative arrangement of 65 two adjoining ring segments and one of the brushes.

Fig. 6 is a detail side elevation of the two contact segments and brush seen in Fig. 5.

Fig. 7 is a face view of the contact disk 70 and contact rings carried thereby.

Fig. 8 is a detail plan view and Fig. 8^a an elevation of a portion of one of the contact rings.

Fig. 9 is a detail sectional view of a portion of a contact disk showing a slightly modified way of attaching the contact segments thereto.

Like numerals of reference indicate like parts throughout the various views. 80

My present invention is capable of embodiment in a variety of forms, and, of course, adapted to represent many views or pictures, the one herein illustrated, however, being deemed sufficient to make clear the 85 general idea and one way of carrying the same into practical effect.

The face of the sign shows a scene or picture of an interior or exterior of any store or building, or in fact pictures of any kind, too 90 numerous to mention, and they may be painted in water or other colors.

The face or front can be made of any semi-transparent material, as paper, cotton-cloth, silk, etc; on the reverse side of the 95 front are drawn figures of persons. These are pictures which give action in the scene to represent a person walking across a room for instance, which is painted on the front.

Pictures of the person or persons are drawn 100 in the proper places in relation to the picture which shows on the front. Each picture is drawn in succession, each succeeding picture having a pose or attitude which a person would naturally assume in the act of walking or running, as the case may be. Around the outline of each figure and excepting the figures described, the paper or other material used is to be coated with a material or paint 105 to make it opaque or light-tight.

110 The picture and figures on the material are tinted with transparent colors to suit

the tastes or conditions. The front is fixed upon a frame which latter may be made of any suitable material, as metal. It consists of a suitably constructed box the size of the 5 picture or sign. Secured within the box are metal partitions which are so arranged as to separate the various figures appearing on the front of the box from each other and forming light-tight boxes or spaces. The 10 depth or height of the partitions is not fixed but is governed by conditions, but there must be space enough between the front and the back to receive electric lamps with some clearance between the latter and the front. 15 The number of lamp receptacles or spaces above referred to must correspond to the number of figures or objects to be shown in the picture. These receptacles are arranged so that the lamps when screwed in will fit 20 between the partitions surrounding the pictures; when the back is placed in position there will be a lamp behind each picture. The lamps are wired up and connected to contact rings or segments on an automatic 25 flasher and when electric current is led to each of these segments in succession the lamps corresponding thereto will be lighted, the arrangement being such that any number of lamps may be lighted at one time, or 30 that some of the lamps may be kept lighted while others are extinguished.

The fact that everything except the figures is opaque allows only that figure to show when the lamp is lighted and it does 35 not show on the front when the lamp is not lighted.

The lamps being lighted in succession one picture after another will be shown and these pictures being in close proximity to 40 each other and having attitudes of a person in the act of walking or running produces a moving effect as a person going from one point to another.

Objects such as electric fixtures, lamps and 45 phrases or reading matter of any kind can be shown as readily as persons, animals, etc.

For exterior use, the sign may be provided with an inclosing frame having a glass covering the front of the device to keep it 50 in good shape to stand weather conditions.

In the present instance I have chosen to show my invention as embodied in a sign representing a restaurant with a lady and gentleman and a waiter. It is evident, however, that the sign may include a greater or 55 less number of persons and may represent other scenes, such as a boot and shoe store, or a drug store, a cigar store, etc.

In the drawings, 1 represents the front or 60 face of the device, said front being made of any semi-transparent material and 2 is a plate which may be made of metal, fiber or other suitable material, preferably opaque, and said parts are carried by any suitably 65 constructed frame 3, which may be of any

suitable shape and dimensions varying with the varying conditions and the character of the picture to be represented.

On the reverse side of the face or front are drawn pictures, as 4, representing in the 70 present instance a waiter, each succeeding picture or representation of the waiter having a pose or attitude which such a person-age would naturally assume in the act of walking into a room through an open door 75 and passing to the table where the guests are seated and bending over to speak to such guests. On the rear side of the front are the figures 5 of a gentleman entering through a separate doorway 6, and a lady, 7, 80 these pictures being so disposed as to represent the lady and gentleman entering the doorway 6 and walking to the table 8 and afterward sitting down in the chairs 9 and 10 respectively. It is to be understood that 85 these pictures are drawn or affixed upon the front or face in proper places in relation to the picture or representation as a whole and that the pictures are so placed that one will not be superimposed upon another or in 90 direct alinement therewith, except in the present instance, the first two pictures of the lady and gentleman entering the room together.

In some instances a glass as 11 may be 95 placed over the face or front, as seen in Fig. 2, to protect the same from the weather when the picture is used for outdoor advertising purposes. Indoors this glass may be omitted. Around the outline of each figure and 100 excepting the figures described, the paper or other material employed for the front is coated with a suitable material or paint to make it opaque or light-tight or light-proof.

The parts 1, 2, 3 and portion 13 constitute 105 a box or inclosure within which are arranged the partitions 14 and 15, preferably of tin, forming means of separating each figure from the other and forming light-tight spaces or receptacles in which electric bulbs 110 16 are placed. It is to be understood that there is a separate lamp for each picture or representation and these lamps are suitably connected up with a source of electricity and said lamps are lighted in accordance with the 115 nature and character of the sign and the picture represented thereby, this, of course, varying with each separate picture or de-sign and also may be varied in the one picture or sign by change of the contacts of the 120 flasher, as will be made apparent as the de-scription proceeds.

It will be understood that the pictures are seen upon the front only when the lamps behind the same are lighted. The lighting of 125 the lamps, however, is so arranged that one picture after another is thrown into view in such rapid succession as to give the effect of a moving or motion picture. Some parts may be shown continuously, as for example 130

the electric ceiling light 17, the tables 8 and 19, and the chairs 9 and 10. This continuous lighting is made possible by a contact brush, presently described, making contact with a 5 long contact section or ring of the flasher. The length of time each picture is seen may be varied by the length of the contact section. It will, of course, be evident that the shorter the contact the shorter the time of exposure 10 of the picture, and the longer the contact the greater the length of time the picture will be seen.

On the front of the sign there may be further desired representations as for instance 15 as seen in Fig. 1, where there will be found displayed the words "What will you have" as seen at 30, the same being represented as coming from the mouth of the waiter, and the words "Corn flakes" as seen at 31 and 32 20 as coming from the mouths of the lady and gentleman respectively.

Any other suitable words may be shown, it being understood that each of the questions 25 and answers will be made visible when the lamps thereof are lighted, which latter takes place at the proper time.

For the purpose of automatically lighting up the various electric lamps to render visible in proper order the different features of 30 the picture and the representations of the persons in the picture, and also for automatically extinguishing such lamps, I provide the means which I will now proceed to describe in detail:

35 The box containing the electric lamps is provided with a rear plate or back 34 having an annular opening 35 within which fits a drum or disk 36 provided with a circumferential flange 37 which lies against the 40 inner face of the back 34 and is secured to the latter by screws 38. The disk is composed of any desired insulating material as fiber, or the like. The disk carries a plurality of metallic rings 39 concentrically 45 arranged, such rings excepting the outermost one, being inserted within recesses in the disk. The outermost ring is divided into a plurality of sections or segments 40 separated by insulating material 41 the sections being 50 secured to the disk by screws 40.

The number of the contact rings as well as the number of the segments may be varied and will depend somewhat upon the number of features or representations which are to be 55 rendered visible in the picture. The size or length of the contact segments and also of the contact surface of the rings will be varied according to the length of time that the representations corresponding to the rings and 60 segments are to be kept visible, the greater the length of a segment or contact surface on a ring the longer time the representations corresponding thereto will be kept visible, and vice versa.

65 Each of the segments of the outermost ring

and each of the other rings excepting the innermost ring is in electrical connection with a lamp 16 by means of a wire 42 secured to the segment and rings, each wire passing through the disk and thence to a lamp. 70

Centrally of the disk there is provided a metallic bushing or sleeve 45 screwed into said disk and threaded interiorly to receive an exteriorly threaded shaft 46 carrying an enlargement 47 having squared faces 48 to 75 adapt it to receive a wrench for unscrewing the shaft from the disk.

Loosely mounted upon the shaft adjacent the enlargement 47 is an arm 49 constructed of some suitable insulating material, as fiber. 80 This arm carries a plurality of contact brushes 50 in electrical connection with a metallic plate 51, the brushes and plate being secured to the arm by screws 52. The contact brushes 50 are of such a length that 85 their outer ends will bear firmly upon the outer faces of the metallic rings and segments. I propose to make the contact of the brushes with the rings and segments a resilient one and for this purpose I construct 90 the brushes of some more or less springy metal and preferably of a plurality of strips, as three, arranged one upon another, the lowermost strip being the longest and the others being successively shorter. In this 95 way I get a better spring contact with the rings and segments.

The brush-carrying arm 49 is preferably beveled off to provide an inclined face 55, one end of the brushes being secured against 100 this inclined face whereby the brushes will lie at an angle relatively to the rings and segments. By arranging the brushes at an angle as described they will have a wiping contact with the rings and segments. Any 105 other suitable way of securing the brushes and plate to the arm may be adopted.

The innermost ring 39 receives electrical current through wire 42' and said current then passes through the innermost brush on 110 the arm 49 and through the metallic strip or plate 51 to the other rings 39 and segments through the respective brushes 50.

For the purpose of obtaining a better illuminating effect of the various figures or 115 objects appearing on the face of the sign, I propose to so construct the brushes that there will be no well defined period between the ending of the illumination of one representation of a person and the beginning 120 of the illumination of the succeeding representation of the same person, thereby producing a more life-like and pleasing effect upon the eye of the observer.

For the attainment of the above object I 125 construct the contact end of each brush at an angle as shown at 56, thus producing a long contact edge on each brush so that in the rotation of the arm 49, as the edge or point 57 of a brush is just about to move 130

out of contact with a segment 40 (see Fig. 8) the edge or point 58 of said brush will be just moving into contact with the adjacent segment. Thus the instant before the 5 lamp connected with the right hand segment seen in Figs. 5 and 6 is extinguished the lamp connected with the left hand segment will be lighted.

For rotating the arm 49 on the shaft 46 10 I employ any suitable type of electric motor 60 which is supported on the shaft 48, the small gear wheel 61 of the reduction gearing of the motor meshing with the large gear wheel 62 loosely mounted on the shaft 46. 15 The speed of the gearing is such that the gear wheel 62 will be turned more or less slowly and this turning movement may be varied in the usual manner by means of a suitable controlling rheostat 60' combined 20 with the motor.

Carried by the gear wheel 62 is a stud or pin 63 threaded in an aperture in said gear wheel and adapted to be adjusted endwise, one end of said stud or pin projecting from 25 one face of the gear wheel 62 sufficiently to strike against and carry around with it the arm 49 when said gear wheel rotates. The motor is to be suitably wired up with a source of electric current, as for instance 30 through the media of wires 64 and when the current is turned on the gear wheel 61 will rotate the gear wheel 62, thus causing the stud or pin 63 to strike against the arm 49 and rotate the latter on shaft 46, where- 35 by the brushes will make sliding or wiping contact with the rings and segments and cause the electric lamps corresponding to the said rings and segments to be lighted.

As long as a brush continues in contact 40 with a ring or segment the electric lamp in connection therewith will be lighted and it will be extinguished as soon as the brush leaves the ring or segment.

By the arrangement of the parts as above 45 described the motor, gear wheel 62, arm 49 and shaft 46 may be bodily removed from connection with the disk by first adjusting the stud or pin 63 in a direction away from the arm 49 so that it will not strike the same 50 and rotate it reversely, and then applying a wrench to the enlargement on the shaft and unscrewing the latter from the disk.

In order that the various parts may be 55 protected from dust, I employ a dust cover 65 which fits detachably over the motor and contiguous parts and engages snugly the circumferential shoulder 66 of the disk.

In cases where an object in the picture is 60 to be displayed for practically the entire time that the rest of the picture is being shown, as for instance the ceiling light, the table and the chairs in the picture shown in the drawings, there may be a ring provided for each one of these objects, or all 65 of them may be made visible simultaneously

by connecting up the lamps for same with the same ring.

Where an entire ring is provided for a particular object in the picture, which object is to be kept visible a part of the time 70 and then temporarily rendered invisible, I would make such ring in one piece but provide a cut-out portion notch or depression 41' in its contact face, as seen in Fig. 8, the length of which depression may be varied, so 75 that when the brush reaches said notch or depression the lamp will be extinguished and so maintained until the brush again bears upon the contact surface of the ring.

In Fig. 9 I show a slightly modified way 80 of securing the contact segments to the disk, said segments 70 being in angular form and embedded in the material of the disk 71 and carrying screws 72 for attachment of the wires leading to the electric bulbs. 85

Having above described the manner in which the invention may be carried out, I will now describe the operation which is as follows: Such parts of the furnishings of the room or other parts of the picture as 90 may be desired may be caused to be shown continuously or for a greater or less length of time. In the present instance the ceiling light 17, as well as the tables and chairs may be shown constantly, that is 95 during the entire length of time that the picture is displayed, and to accomplish this the contact ring of the flasher will be continuous if such parts are to be displayed continuously, or with an uninterrupted contact surface corresponding to the length of time they are to be displayed. The other objects are thrown into view, for instance, as follows: the lamps are so connected up with the sections and rings that the 100 picture of the lady and gentleman entering the room through the door 6 are first thrown into view; then the next will be the picture of the lady and gentleman proceeding, then the picture of the lady seated in a chair, then 105 that of the gentleman passing around the table to the chair at the other side of the latter, and then the picture of the gentleman seated in the chair 10. The lady sitting in the chair and the gentleman sitting in the 110 other chair are then caused to remain in view, it being understood that the other representations of said persons are caused to disappear one after another by reason of the brushes being no longer in contact with the 115 particular ring sections therefor. Then the picture of the waiter is shown entering the door and by means of the proper contacts between the brushes and the ring sections each succeeding picture is shown until the waiter 120 is shown at the back of the chair of the gentleman, it being understood that all of the other pictures of the waiter are thrown out of view in rapid succession. The pictures are thrown into view with such rapid suc- 125 130

cession that they are given the appearance of a person in motion.

As soon as the picture of the waiter is shown at the back of the chair, the words 5 "What will you have" are next shown and then as they disappear from view the words "Corn flakes" are shown as if issuing from the mouths of the lady and gentleman simultaneously. Then all of the lights are extinguished, including or not those behind the lamp 17 and the tables and chairs as may be desired.

The flasher is arranged so that after an interval of say a minute, more or less, the 15 same mode of procedure is followed and the sign again illuminated in the same way. This may continue for any given length of time, flashing at predetermined intervals for as many hours as the party for whom the 20 advertisement is displayed may wish.

Of course it will be understood that when the sign is made for other sorts of displays the pictures are differently arranged and will be varied in character accordingly.

25 From the foregoing it will be seen that I have devised a simple yet very effective sign giving a moving picture effect and while the structural embodiment of the invention as herein disclosed is what I consider preferable at the present time, it is evident that 30 the same is subject to changes, variations and modifications in detail, proportion of parts, etc., without departing from the spirit of the invention or sacrificing any of its advantages. I, therefore, do not intend to 35 restrict myself to such details as are herein disclosed but reserve the right to make such changes, variations and modifications as come properly within the scope of the invention.

40 What I claim and desire to secure by Letters Patent is:

1. In a switch mechanism for flashing electric lights of a box advertising sign substantially as disclosed, a disk of insulating material carried by the boxing, a plurality of contact sections carried by the disk and insulated from each other, electrical connections between the said sections and the electric lamps, a shaft mounted in the disk, a brush-carrying arm of insulating material loosely mounted on the shaft, a metallic brush secured to the arm and bearing upon the successive sections, an electrical motor 45 mounted on the said shaft, a gear wheel also loosely mounted on the shaft, a pin carried by the gear wheel and adapted to rotate the brush-carrying arm, and gearing between the motor and said gear wheel.

60 2. In a switch mechanism for flashing electric lights of a box advertising sign substantially as disclosed, a disk of insulating material carried by the boxing, concentrically arranged contact rings carried by the disk, 65 one of which rings is divided into a plural-

ity of sections insulated from each other and the other rings having their contact surfaces cut away at intervals, electrical connections between the various rings and the electric lamps, a shaft mounted in the disk, 70 a brush-carrying arm of insulating material loosely mounted on the shaft, metallic brushes secured to the arm and making contact with the rings, an electrical motor mounted on the said shaft, a gear wheel 75 also loosely mounted on the shaft, a pin carried by the gear wheel and adapted to rotate the arm, and gearing between the motor and said gear wheel.

3. In a switch mechanism for flashing electric lights of a box advertising sign substantially as disclosed, a disk of insulating material carried by the boxing, a plurality of contact sections carried by the disk and insulated from each other, electrical connections between the said sections and the electric lamps, a shaft mounted in the disk, a brush-carrying arm of insulating material loosely mounted on the shaft, a metallic brush secured to the arm and bearing upon 90 the successive sections, an electrical motor mounted on the said shaft, a gear wheel also loosely mounted on the shaft, a pin adjustably carried by the gear wheel and adapted to rotate the brush-carrying arm, and gearing 95 between the motor and said gear wheel.

4. In a switch mechanism for flashing electric lights of a box advertising sign substantially as disclosed, a disk of insulating material carried by the boxing, a plurality of contact sections carried by the disk and insulated from each other, electrical connections between the said sections and the electric lamps, a shaft mounted in the disk, a brush-carrying arm of insulating material 100 loosely mounted on the shaft, a metallic brush secured to the arm and adapted to bear upon the successive sections, said brush having its contact edge arranged at an angle and of a predetermined length relatively to 110 two adjacent sections of the contact ring, an electrical motor mounted on the shaft, a pin carried by the gear wheel and adapted to rotate the brush-carrying arm, and gearing between the motor and the said gear 115 wheels.

5. In a switch mechanism for flashing electric lights of a box advertising sign substantially as disclosed, a disk of insulating material carried by the boxing, a plurality of contact sections carried by the disk and insulated from each other, electrical connections between the said sections and the electric lamps, a shaft threaded in a threaded opening in the disk, a brush-carrying arm of insulating material loosely mounted on the shaft, a metallic brush secured to the arm and adapted to bear upon the successive sections, an electrical motor mounted on the said shaft, a gear wheel also loosely mounted 125 130

on the shaft, said motor, gear wheel, arm and shaft being adapted for removal bodily from the disk when the shaft is unscrewed therefrom, a pin carried by the gear wheel 5 and adapted to rotate the brush-carrying arm, and gearing between the motor and said gear wheel.

6. In a switch mechanism for flashing electric lights of a box advertising sign substantially as disclosed, a disk of insulating material carried by the boxing, a plurality of contact sections carried by the disk and insulated from each other, electrical connections between the said sections and the 10 electric lamps, a shaft mounted in the disk, a brush-carrying arm of insulating material 15 loosely mounted on the shaft, a metallic

brush secured to the arm, said brush being composed of a plurality of superposed metallic plates, the lowermost one of which 20 is adapted to bear upon the successive sections of the ring, an electrical motor mounted on the said shaft, a gear wheel also loosely mounted on the shaft, a pin carried by the gear wheel and adapted to rotate the 25 brush-carrying arm, and gearing between the motor and the said gear wheel.

In testimony whereof I affix my signature in the presence of two witnesses.

GEORGE S. COLEMAN.
